UNITED STATES PATENT OFFICE.

GEORGE T. WOHLFORD, OF WIGGINS, COLORADO.

PUMP-ROD CONNECTOR.

1,212,868.

Specification of Letters Patent. Patented Jan. 16, 1917.

Application filed April 12, 1916. Serial No. 90,721.

To all whom it may concern:

Be it known that I, GEORGE T. WOHLFORD, a citizen of the United States, residing at Wiggins, in the county of Morgan and State 5 of Colorado, have invented certain new and useful Improvements in Pump-Rod Connectors, of which the following is a specification.

The present invention has to do with improvements in connector devices especially adapted for windmill pump rods, the object in view being to provide a simple article of manufacture consisting of a single piece of material so formed as to provide a connecting pin and locking means therefor to prevent accidental displacement of the pin.

For a full understanding of the present invention, reference is to be had to the following description and the accompanying 20 drawing, in which:

Figure 1 is a side elevation of a portion of the wind mill and pump rods having the connector device of this invention attached in connecting position, said figure showing in dotted lines the initial position of the pin preliminary to movement of the locking element thereof into locking position. Fig. 2 is a view in elevation at right angles to the view of Fig. 1, parts being broken away and 25 shown in section. Fig. 3 is a detail view of the connector device alone.

Throughout the following detail description, and on the several figures of the drawing, similar parts are referred to by like 35 reference characters.

Referring to the drawing the numeral 1 represents the lower end portion of a windmill rod having the usual guide sleeve 2 at its lowermost extremity and 3 designates the 40 upper end portion of the pump rod adapted for connection to the rod 1. The rods are provided as usual with suitable openings to receive the connector device which forms the subject matter of this application. Said device consists essentially of a single piece of 45 rod metal bent laterally from its length to form a fingerpiece or loop 4. One end portion or side of the device is perfectly straight and constitutes the connecting pin, 50 designated 5 which is adapted to be inserted in the rod openings when the latter are in registering position. The other side or end portion of the device is bent laterally from

the loop 4 and again bent to provide the arm 6 which passes about the side of the rod 55 1 as shown in Fig. 1 of the drawing when the pin is inserted in connecting position. This arm 6 terminates in the angularly bent extremity 7, the latter element constituting the locking element adapted to engage with the 60 side of the rod 1 to prevent displacement of the pin from connecting position.

In the use of the article above described, which is preferably connected by the chain 8 to the windmill rod for the purpose of 65 convenience it is designed to be inserted in connecting position by passing the pin 5 through the apertures of the rods 1 and 2, in the manner shown in dotted lines in Fig. 1 and the offstanding arm 6, by reason of its 70 position will tend to gravitate to the full line position of this figure, moving about the pin 5 as an axis, so as to bring the angularly bent extremity 7 into coöperative position with the side of the pump rod opposite the 75 side of insertion of the pin thereinto. By reason of the gravitational tendency above referred to the accidental displacement of the pin from position resulting in the disconnection of the rods is eliminated. 80

It will be observed that the portion of my device which is laterally bent from the loop 4 constitutes an abutment limiting the movement of the pin 5 as when being moved to an operative connecting position, and when 85 said abutment performs its abutting function the operator may release the device and it will gravitate into locking position. Furthermore, the provision of the finger piece and loop 4 affords a convenient means for 90 grasping and manipulating the device without liability of soiling the fingers by grease usually provided on parts which will be connected by the invention, the finger piece 4 likewise being a loop for enabling connection with the chain 8, the innermost portion of which loop is closed by contact thereof with the pin 5.

Having thus described my invention, what I claim as new is:

As a new article of manufacture, a connector for pump rods and the like, the same comprising a single piece of rod metal, one end of which constitutes a connecting pin, the rod being bent upon itself at one end of 165 the pin whereby to form a loop constituting

a finger piece and a means for connecting the connector with a displacement preventing device, and said rod being further bent laterally from the top to form an abutment 5 limiting the movement of the pin to its operative connecting position, after which the rod is bent to form an arm parallel with

the pin and having a laterally extending extremity constituting a locking element whereby to prevent displacement of the connector when disposed in operative position. 10

In testimony whereof I affix my signature.

GEORGE T. WOHLFORD.
